UNITED STATES PATENT OFFICE

158,833

CIGARETTE HOLDER

Charles S. Beller, New York, N. Y.

Application September 15, 1949, Serial No. 5,002

Term of patent 7 years

(Cl. D85—2)

To all whom it may concern:

Be it known that I, Charles S. Beller, a citizen of the United States and resident of the city of New York, county of Kings, Borough of Brooklyn, and State of New York, have invented a new, original, and ornamental Design for a Cigarette Holder, of which the following is a specification, reference being had to the accompanying drawing, forming part thereof in which:

Fig. 1 is a front elevational view of a cigarette holder, showing my new design;

Fig. 2 is a side elevational view of the same; and

Fig. 3 is a top plan view of the same.

I claim:

The ornamental design for a cigarette holder, substantially as shown.

CHARLES S. BELLER.
